UNITED STATES PATENT OFFICE.

JAMES ALLEN KAMMERDINER, OF LOS ANGELES, CALIFORNIA.

ROTARY JAR.

Application filed April 13, 1925, Serial No. 22,584. Renewed November 22, 1926.

This invention relates to a rotary jar for use in well drilling apparatus, and is especially useful in fishing jobs wherein lost tools, articles, or parts are stuck in the hole and must be dislodged. I have disclosed a device of this character in United States Letters Patent for rotary jar reissued to me February 12, 1924, No. 15,760, and Letters Patent granted to me March 10, 1925, No. 1,529,544.

Jars of this type comprising relatively rotatable hammer and anvil sections have been set by rotating the sections. They are then released by rotation thereof in the opposite direction. Safety joints are commonly placed in the string of pipe or rods supporting the jar, and are easily unscrewed by turning the string of pipe in a direction opposite to that for tightening the threads. Setting of the jar must be effected by turning in one direction and tripping must be effected by turning in the opposite direction. If this is done by turning the string from above, there is a tendency to open the string at the safety joints. It is the primary object of this invention to provide a jar having means to automatically set the same by pressure thereon. It is another object of this invention to provide means which will be effective in assisting the impact blow of the jar upon tripping.

These objects together with other objects and corresponding accomplishments are obtained by means of the embodiment of my invention illustrated in the accompanying drawing, in which:

Fig. 1 is an axial section through a jar in expanded position; Fig. 2 is a similar view of the jar in contracted position; Fig. 3 is a section as seen on the line 3-3 of Fig. 1; Fig. 4 is a section as seen on the line 4-4 of Fig. 1; and Fig. 5 is a section as seen on the line 5-5 of Fig. 1.

Referring more particularly to the drawing, a cylindrical body or cage 6 is provided with a tapered threaded pin 7 at the upper end, and has a bore 8 extending therethrough. The body is internally threaded at the lower end, and mounted therein is a closure member 9 forming an anvil. The upper end of the bore is reduced in diameter to form a plunger chamber 10. Within the bore is a mutilated thread 11 formed of two diametrically opposed portions, each occupying approximately one quarter of the

periphery. Fillets 12 forms stops for the threads.

Disposed within the cage is a hammer comprising a cylindrical head 13 adapted to engage the anvil 9. The hammer head is provided with a tubular mandrel 14 which slidably extends through the bore in the anvil. This mandrel is provided at its lower end with a threaded pin 15 for attaching any suitable device thereto, such as a string of pipe. A shank 16 is extended above the head and is provided with threads 17 for meshing with the corresponding threads on the cage. These threads form in effect shoulders which are inclined to the axis of the cage and may also be provided with fillets to form stops. The shank is extended upwardly to form a tubular plunger 19 slidably mounted in the chamber 10. At the upper end of the plunger are cup leathers 20. The hammer member has a cylindrical bore extending therethrough so that a circulation fluid passage is formed from the pin 7 through the body to the pin 15. This construction provides for connecting the tool in a circulation line. Mounted over the shank 14 is a left hand compression spring 21. One end of the compression spring is mounted in the plug 9 and held in position by a set screw 22. The other end rests in a recess in the pin 15. The construction is such that if the shank is parted, the spring will remain with the anvil section and may be moved from the hole.

The jar is placed in a string of tubing or pipe, a fishing tool depending from the bottom of the string. Upon getting a grip upon the "fish" the jar is telescoped by lowering the string. This causes the spring 21 to be compressed with a consequent rotation. The rotation of the sections causes the segments of the thread on the hammer shank to slide between the segments of the thread on the cage. The fillets prevent the hammer from riding out of mesh with the cage thread, and furthermore, in this position continuous rotation of the string may be effected. The enlargement of the chamber on one side of the hammer head is counteracted by the reduction on the other side.

Projecting laterally from the shank are lugs 23. These lugs are diametrically opposite to one another and are positioned in line with the mouths of the thread on the shank so that as the shank is moved upwardly, the

hammer cannot be turned until the threads on the hammer and cage register, whereupon the lugs ride over the edges of the thread 11, and the parts are turned so that they 5 mesh. Upon telescoping of the jar from the position shown in Fig. 1 to that shown in Fig. 2 there is a torsional force exerted tending to rotate the sections relative to one another. As soon as the threads register, they 10 are free to turn, and the spring action moves them into engagement. Having placed the threads in mesh, a pull is exerted upon the string, and after the proper tension has been reached, the jar is turned or rotated. Rotation 15 of the two parts causes the segments of the threads to ride out of mesh and trip, whereupon the hammer strikes the anvil causing a jar or impact upwardly. Iron or metal pipe or tubing used in oil well work 20 has elasticity which is very appreciable in a string of the length commonly used in wells. This elasticity assists in creating the jarring effect upon release of the hammer.

What I claim is:

25 1. A rotary jar for use in well drilling comprising a rotary hammer member and a rotary anvil member telescopically connected, each of the members having trip shoulders, said shoulders being interrupted to permit the passage of the shoulders on the hammer member past the shoulders on the anvil member and when said shoulders are in engagement further longitudinal movement of the members is prevented, but when 30 out of engagement longitudinal movement of said members is permitted, and means operated by closure movement of said members to turn said shoulders into engagement.

2. A rotary jar for use in well drilling 35 comprising a rotary hammer member and a rotary anvil member telescopically connected, each of the members having trip shoulders, said shoulders being interrupted to permit the passage of the shoulders on the hammer members past the shoulders on the

anvil member and when said shoulders are in engagement further longitudinal movement of the members is prevented, but when out of engagement longitudinal movement of said members is permitted, and resilient means connecting said members and operated by closure movement of said members tending to turn them into shoulder engaging position.

3. A rotary jar for use in well drilling 55 comprising a rotary hammer member and a rotary anvil member telescopically connected, each of the members having trip shoulders, said shoulders being interrupted to permit the passage of the shoulders on the hammer member past the shoulders on the anvil member, and when said shoulders are in engagement further longitudinal movement of the members is prevented, but when out of engagement longitudinal movement of said members is permitted, and a helical compression spring connected at one end to said anvil member and at the other end 60 said hammer member.

4. A rotary jar for use in well drilling 70 comprising a rotary anvil cage, a rotary hammer telescopically mounted in said cage, the hammer and anvil having trip shoulders, said shoulders being interrupted to permit the passage of the shoulders on the hammer past the shoulders on the anvil and when said shoulders are in engagement further longitudinal movement of the hammer and anvil is prevented but when out of engagement longitudinal movement of said 75 hammer and anvil is permitted, and a helical compression spring connected at one end to said anvil and at the other end to said hammer so arranged that closure of said anvil and hammer tends to turn them into 80 shoulder engaging position.

In witness that I claim the foregoing I have hereunto subscribed my name this 4th day of April, 1925.

JAMES ALLEN KAMMERDINER.
